UNITED STATES PATENT OFFICE.

VICTOR RALPH NICHOLSON, OF BELLEVUE, CORK, IRELAND.

INTERNAL-COMBUSTION ENGINE.

SPECIFICATION forming part of Letters Patent No. 733,417, dated July 14, 1903.

Application filed January 3, 1903. Serial No. 137,687. (No model.)

To all whom it may concern:

Be it known that I, VICTOR RALPH NICHOLSON, a subject of the King of Great Britain, residing at Bellevue, Cork, Ireland, have invented new and useful Improvements in Internal-Combustion Engines, of which the following is a specification.

This invention relates to internal-combustion engines, the improvements referring mainly to the construction of the combustion-chamber, vaporizer, and igniter.

According to the invention I provide in connection with the combustion-chamber of the cylinder and at that end thereof farthest from the cylinder a chamber into which the vapor (from the vaporizer in the case of an oil-engine) flows through an inlet-valve, the said vapor being then drawn during the suction action of the piston directly into the combustion-chamber through an opening between the two chambers. In conjunction with the combustion-chamber and the auxiliary chamber I also provide a third chamber or a tube, which connects the auxiliary chamber to the combustion-chamber by small openings, this chamber or tube forming the igniter. In the case of a heavy oil-engine the oil may be vaporized in a chamber formed with a suitable portion of the external side of the combustion-chamber and the vapor led to the said vapor-valve by means of a passage or pipe. With this arrangement during the suction action of the engine the vapor is drawn into the auxiliary chamber through the vapor-valve, the major portion of the said vapor being thence drawn directly into the combustion-chamber and the remaining portion passing into the said chamber through the igniter, this latter portion being on the compression-stroke of the piston ignited, so as to explode the charge in the combustion-chamber. In practice I prefer to make use of an igniter comprising a casing having an internal bulb or tube provided with a number of ribs, which retain the heat and offer a large surface to the vapor coming in contact with them.

The engine may be governed either by controlling the vapor-valve or by controlling the amount of air or oil which is admitted to the engine.

In the accompanying drawings, Figure 1 is a vertical section of a combustion-chamber and vaporizer made according to the invention and shown applied to an oil-engine cylinder. Fig. 2 is a sectional plan view, and Fig. 3 a sectional end elevation thereof.

a represents the cylinder, *b* the combustion-chamber, and *c* the vaporizing and mixing chamber, the said vaporizer being attached to the outside of the combustion-chamber *b*, as clearly shown in Figs. 1 and 2, and being provided with internal partial partitions *c'c'*, whereby the oil, which enters through the inlet *d*, is drawn by the air entering through the air-inlet *d'* in a zigzag path, so as to be presented to an extensive heating area before passing to the combustion-chamber.

e is the auxiliary chamber, which is in connection with the vaporizer by the passage *f*. This passage is controlled by the valve *g*, which normally closes it under the action of the spring-piston *g'*. The auxiliary chamber *e* is also in communication with the combustion-chamber *b* by means of the passage *h*.

i is the chamber or tube or by-pass which connects the auxiliary chamber *e* to the combustion-chamber *b* by small openings *j* and *k*, respectively. This chamber *i* contains the ignition device, which in the form shown in the drawings comprises a tube *l*, having the internal swellings or ribs *m m*, which retain the heat and offer a large surface to the vapor coming in contact with them.

n is the main air-inlet valve, and *o* the exhaust-valve.

The operation of an engine having my improvements applied thereto is as follows: The oil entering the vaporizer *c* through the inlet *d* is during the suction-stroke of the piston drawn by the air entering through the inlet *d'* through the said vaporizer and thence through the valve *g* into the auxiliary chamber *e*, where it divides, the major portion of it being drawn directly to the combustion-chamber *b*, while the remainder flows through the tube or chamber *i* into the said combustion-chamber *b*, this latter portion on the following compression-stroke of the piston being ignited, so as to explode the charge in the combustion-chamber.

Having now particularly described and as-

certained the nature of my said invention and in what manner the same is to be performed, I declare that what I claim is—

1. In an internal-combustion chamber, the combination with a cylinder provided with a combustion-chamber, of a mixing-chamber, having a direct communication by large openings with the combustion-chamber and a by-pass of reduced area for conveying a portion of the explosive mixture to said combustion-chamber, and an igniter located in the by-pass, substantially as described.

2. In an internal-combustion chamber, the combination with a cylinder provided with a combustion-chamber external thereto and

communicating directly by a single aperture with the cylinder, of a vaporizing and mixing chamber, an intermediate mixing-chamber connected thereto, said mixing-chamber having a direct communication by large openings with the combustion-chamber and a by-pass of reduced area for conveying a portion of the mixture from the mixing-chamber to the combustion-chamber and an igniter located in the by-pass, substantially as described. 25

VICTOR RALPH NICHOLSON.
